UNITED STATES PATENT OFFICE.

BERNHARD LUNDBERG, OF CHICAGO, ILLINOIS.

CARD-DISPLAY FRAME.

Application filed January 12, 1922. Serial No. 528,624.

To all whom it may concern:

Be it known that I, BERNHARD LUNDBERG, a citizen of the United States, residing at Chicago, in the county of Cook and State of Illinois, have invented a new and useful Improvement in Card-Display Frames, of which the following is a specification.

My invention relates to frames for holding display cards and the like and has for one of its objects the provision of a simple and efficient arrangement in a frame construction for quickly and easily changing cards or pictures or the like when desired.

A further object is the provision of a frame for holding pictures, cards and the like which will be substantially dust tight.

A still further object is the provision of a frame having a tray adapted to automatically slide out of the frame when released so as to receive a picture or card or for easily removing or replacing the latter.

Other objects will appear hereinafter.

An embodiment of my invention is illustrated in the accompanying drawing forming a part of this specification and in which

Fig. 1 is a top view of a portion of a frame embodying my invention;

Fig. 2 is a section of the same taken on line 2—2 of Fig. 1; and

Fig. 3 is an end view of the device.

Referring more particularly to the drawing, I have indicated a portion of a frame made up of sides 4 and 5 and an end 6. In the form of the invention illustrated the frame parts 4, 5 and 6 may be of wood or other desired material and connected together by glue or in any desired manner. The frame is recessed in its back portion to receive a glass 7 such as is usually used in conventional picture frames. Behind the glass 7 in the frame is a backing plate 8 which may be held in position by means of pins or tacks 9 or in any other desirable manner. Between the glass 7 and back plate 8 is a space in which a tray 10 is mounted. The glass 7 and plate 8 form guides for holding the tray 10 in position.

Along the edges of the tray 10 are turned up flanges 11 which serve to hold the card or picture 12 in position. The flanges 11 extend high enough to engage the glass 7 and provide a space between the bottom of the tray 10 and the glass for the picture card 12.

At one edge of the frame I provide means for withdrawing the tray far enough to ex-

pose the picture card for replacing the latter. In the form shown I have indicated this opening as being in the end 6, but it will be apparent that any of the edges of the frame may be utilized for this purpose. The end 6, as shown, is provided with a recess 13 in which a block 14 is fitted. The tray 10 has an end portion 15 adjacent the block 14 bent up against said block and held to the latter by screws 16, one of which is indicated in Fig. 2. The block 14 may be attached to the tray in any desirable manner. The block 14 preferably fits the recess 13 snugly so as to exclude dust. When desired pieces of felt 17 may be provided between the block 14 and the bottom of recess 13 so as to make sure that no dust can enter the frame.

The tray 10 intermediate its ends has two ears 18 formed thereon which extend into grooves 19 in the sides 4 and 5. Disposed in said grooves are springs 20 which are attached to the ears 18 and to pins 21 in the frame parts 4 and 5. These springs are preferably tension springs and tend to pull the tray towards the recess 13. A pin 22 is indicated as passing into end 6 through a suitable opening in tray 10 to hold the tray in the frame against the influence of springs 20. I have shown a short pin 22 entering the part 6 from the back, but it will be understood that this pin or locking member may pass through any suitable part of the frame or pass into the frame in any suitable manner to hold the tray in the position indicated. Upon withdrawing the pin 22 the tray will be moved out into the position indicated in dotted lines in Figs. 1 and 2, so as to make the picture card easily removable.

The tray bottom 10 has openings 23 formed therein adjacent the block 14 so that one can introduce his fingers in said opening to bend the card out away from the bottom of the tray to make it easily removable. These openings 23 preferably extend closer to the block 14 than the picture card can come, so that when desired a person can introduce his finger nails in an opening 23 against the edge of a picture in the frame to facilitate removing the latter. To insure this stops 24 are formed in the tray at points spaced from the block 14 to prevent the picture from entirely covering the openings 23.

With this construction the parts making up the front of the frame are all secured together rigidly and can be finished in any desirable manner. This arrangement is pro-

vided so that dust-tight joints can be made. This is desirable since frames of this character are of use to display advertising matter where exposed to dust and which would 5 not be attractive should they become filled on the inside with dust. Should the glass 7 become broken it is only necessary to move the tray to the position indicated by dotted lines in Fig. 2 and remove back plate 8 by 10 taking out pins 9. The glass can then be moved out of its position indicated from the end of the frame where the tray has been moved away from it. The new glass can be inserted at the same position and the back- 15 ing plate again put in place.

I claim:

1. A display device comprising a frame; a picture tray slidably mounted in the frame; ears on opposite sides of the tray; 20 springs connected with the ears and frame tending to move said tray in one direction; and a lock holding the tray against the influence of said springs.

2. A display device comprising a frame; 25 a picture tray slidably mounted in the frame, there being spaces between adjacent sides of the frame and tray; ears on the tray extending into said spaces; springs in said spaces attached to said ears and frame; and means locking the tray against 30 movement in the frame.

3. A display device comprising a frame; a picture tray slidably mounted in the frame; picture stops in the tray spaced 35 from one edge of the latter, there being an opening in the bottom of the tray having a portion disposed between the end of the tray and a line passing through said stop parallel to the end of the tray.

40 4. A display device comprising a frame having its sides and ends all secured rigidly together and a recess in one end below the upper surface of the latter; a picture tray slidably mounted in the frame 45 with one end at said recess; a block attached to the tray substantially filling the

recess; a spring tending to move the tray towards said recess; and a pin extending through the tray and into the frame for locking the tray against the influence of 50 said spring.

5. A display device comprising a frame having a slot in one end and grooves in opposite sides; a tray slidably mounted in the frame; ears on the tray extending into 55 said grooves; springs in the grooves attached to the frame and ears; and a member attached to the tray disposed in and filling said slot.

6. A display device comprising a frame 60 having a slot in one end and grooves in opposite sides; a tray slideable in said frame; ears on the tray extending into said grooves; springs secured to said ears and frame tending to move the frame towards 65 said slot; and a lock securing the tray to said frame holding the latter against the influence of said spring.

7. A display device comprising a frame having a recess in one end and grooves in 70 opposite sides; a tray slideable in the frame with portions extending to said grooves and one end adjacent said recess; springs in said grooves attached to the frame and tray; a block in and substantially filling 75 said recess and attached to the tray; and a lock locking the block in said recess.

8. A display device comprising a frame having a slot in one edge and a guide extending away from said slot; a tray in said 80 guides with one end adjacent said slot and an opening in the bottom of said tray adjacent said slot; a block attached to said tray and substantially filling the outer end of said slot; and picture stops in the tray adapted to hold a picture in a position to prevent entire covering of said openings.

In testimony whereof I have signed my name to this specification on this 10th day of January, A. D. 1922.

BERNHARD LUNDBERG.
